DRAFT REGULATOR FOR ORCHARD
HEATERSJames R. Campbell, Ontario, Calif., assignor to
William C. Scheu, Upland, Calif.

Application October 17, 1938, Serial No. 235,299

8 Claims. (Cl. 158—91)

This invention relates to temperature-controlled draft regulators for liquid fuel orchard heaters and is concerned particularly with heat-responsive devices for automatically establishing a controlled influx of combustion air to the fuel vaporizing chamber of such a heater for normal burning operation thereof following the starting or ignition period of such a heater.

The heat-responsive draft-regulating device of this invention is primarily adapted for use with vaporizing type liquid fuel orchard heaters. In heaters of this type a vaporizing flame is maintained at or near the surface of the body of fuel contained in the heater to cause vaporization from the surface of this fuel. The oil vapors pass upwardly into a stack where additional air is mixed with them to cause substantially complete combustion of the vapors in a main flame at a point removed from the vaporizing flame. A heater of this general type provided with such a stack forming a main combustion chamber is shown in U. S. Patent No. 1,930,863, issued October 17, 1933, to William C. Scheu.

Heaters of this type are provided with one or more air-admitting openings in the body communicating with the vaporizing chamber to admit air to the vaporizing flame in the vaporizing chamber. With such arrangement it is preferable to supply a relatively large quantity of air to the vaporizing chamber to support the vaporizing flame when the heater is first ignited and until the vaporizing chamber has been heated. After the vaporizing chamber has become heated and the main combustion flame is well established, a smaller amount of heat from the vaporizing flame is required to vaporize fuel; and if the air supply is not reduced to diminish the flame, there will be a tendency to vaporize an excess quantity of fuel. These relations are all a function of the heat generated in the vaporizing chamber and are substantially independent of the temperatures existing where the main combustion takes place in the stack, or at any other place removed from the vaporizing flame.

In order to obtain proper and satisfactory operation of such a liquid fuel heater it is desirable to restrict the flow of air admitted to the vaporizing chamber after a sufficient quantity of heat has been generated therein. In many cases this operation is performed manually or not at all due to the labor involved. When this operation is not performed the heater consumes an excess quantity of fuel and often smokes badly, thus wasting fuel.

The principal object of the invention is to provide a heat-controlled draft-regulating device for use in connection with a vaporizing type of liquid fuel orchard heater, which is operable to provide a substantially unrestricted inflow of air into the vaporizing chamber during a preliminary ignition period and to restrict automatically the admission of air to said vaporizing chamber when the ignition is completed, in response to a temperature increase resulting from the heat generated within the vaporizing chamber of the heater, so as to thereafter maintain the relatively restricted admission of air to the chamber in quantities sufficient to maintain the desired normal burning rate during subsequent operation of the heater.

A further object of the invention is to provide a heat-responsive draft-regulating device for use in association with a vaporizing type liquid fuel orchard heater, which is rugged, simple in operation and construction, and which may be readily removed for repair or for transfer to another heater where it may be readily installed.

Further objects and advantages of the invention, of which the above are typical, will become apparent as the description proceeds.

The draft-regulating device of my invention may comprise a pivotally mounted regulating plate which is disposed adjacent an air-admitting opening communicating with the vaporizing chamber of a liquid fuel orchard heater in which a vaporizing flame is maintained within the heater at a place removed from the main flame. The draft-regulating plate is movable between a first position which provides the maximum access of air to the vaporizing chamber through the air-admitting opening and a second position restricting the passage of air through the air-admitting opening. The draft-regulating plate is biased toward the second position in which the passage of air through the opening is restricted. Thermostatic means, such as a bimetallic element, is disposed in heat-receiving relation to the vaporizing flame in the heater and is adapted to hold the plate in the first position and is operable in response to the heat generated by the vaporizing flame in the vaporizing chamber to release the plate and permit the plate to move into the second position.

It is highly desirable that the device operate in such manner as not to cut off completely the air admitted to the vaporizing chamber. This may be accomplished by shaping the regulating plate so that it does not conform to and does

not cover the entire air opening. Or it may be accomplished by providing limiting means, either fixed or movable for adjustment, that limits the movement of the plate toward the second position to a position at which the opening is not entirely closed and the passage of air is restricted but not stopped, or both of the above means may be used to accomplish this object.

How the above, as well as other objects and advantages of my invention are attained will be more readily understood by reference to the following description, and the annexed drawings, in which:

Fig. 1 is a fragmentary vertical section through the base of a vaporizing type orchard heater provided with the draft-regulating device of my invention, the draft-regulating plate being shown in an open or substantially non-restricting position;

Fig. 2 is a fragmentary plan view of the draft-regulating device taken from above on line 2—2 of Fig. 1;

Fig. 3 is an enlarged fragmentary vertical section through the draft-regulating device in the aspect of Fig. 1, showing the draft-regulating plate in a closed or air-restricting position;

Fig. 4 is an inverted plan view of the draft-regulating device taken on line 4—4 of Fig. 3, with the insulating cover over the bimetallic element removed;

Fig. 5 is a view similar to Fig. 4 of the draft-regulating device alone, except that the insulating cover of the bimetallic strip is in place and the draft-regulating plate is shown in an open position;

Fig. 6 is a vertical section through the draft-regulating device on line 6—6 of Fig. 3;

Fig. 7 is a plan view of a draft-regulating device showing a variational form of draft-regulating plate;

Fig. 8 is a vertical section through Fig. 7, partially in elevation, showing the variational form of plate in cross-section; and

Figs. 9 and 10 are views similar respectively to Figs. 7 and 8, showing another variational form of draft-regulating plate.

There is shown in Figs. 1 to 3 of the drawings a portion of a standard type of vaporizing liquid fuel orchard heater, indicated generally at 10. The orchard heater comprises a bowl 11 which not only provides a base for supporting the upper structure but also forms a reservoir that contains a body of liquid fuel 12 which is vaporized in bowl 11 and burned in the heater stack. Bowl 11 is provided with a cover 14 which has a centrally disposed collar portion 14a around which the lower end of stack 15 fits snugly. The stack may be of any type suitable for orchard heaters, the exact kind being immaterial as far as the present invention is concerned.

The space 16 above the fuel body 12 and enclosed by the walls of bowl 11 and cover 14 constitutes a vaporizing chamber. A suitable opening defined by the raised collar portion 17 of cover 14 is provided in order to admit air to the vaporizing chamber for maintenance of the vaporizing flame therein. The collar portion 17 also forms a mounting means for the draft-regulating device described later. A draft tube or flame-stabilizing baffle 18 is preferably provided to facilitate the maintenance of a vaporizing flame within chamber 16. The upper end of draft tube 18 is preferably provided with an out-

wardly extending flange which engages the inwardly turned flange on raised collar 17 as shown to support the draft tube, which extends downwardly from the wall of cover 14 into the oil body 12 as illustrated in Fig. 1. The upper end of draft tube 18 is open for the admission of air which enters the vaporizing chamber through the draft tube. A suitable wick 19 is preferably provided adjacent the upper end of tube 18, the wick member taking any suitable form, such as the body indicated, and is preferably of fibrous asbestos or other porous material. The wick is preferably wrapped or enclosed in a foraminous metal envelope 20 which holds the wick in place and yet permits access of oil to the lower portion of the wick.

As may be seen best from Fig. 3, draft tube 18 is provided with an opening 22 just beneath the top flange at the lower or left-hand side as viewed in Fig. 3. A short lug 23 projects inwardly through opening 22 from the rim of collar 17. This construction not only assures that the draft tube will be inserted through collar 17 and maintained in the proper position, but the lug also locks the draft tube to cover 14 against accidental removal.

The draft-regulating device indicated generally at 25 comprises body 26 having an air-admitting opening 27, a draft-regulating plate 28 pivotally mounted adjacent opening 27 and adapted to control the flow of air through the opening, and a bimetallic thermostatic element 30 enclosed within an insulating housing 31 and adapted to effect closure of the draft-regulating plate. Body 26 is of circular outline and has a depressed central portion which is of proper diameter to fit snugly within the open upper end of draft tube 18. The vertical wall portion of the body formed by the central depression is indented at 32 to receive lug 23 (see Figs. 4 and 5). A similar indentation 33 is made in the body opposite indentation 32, the indentation 33 receiving the folded seam in draft tube 18. The two indentations 32 and 33 being of a different size and shape, it is possible to insert body 26 into the upper end of draft tube 18 in only one position. This construction has the advantage that the draft-regulating device is always held in the proper position, and the devices in all the heaters are in the same position, the uniformity of position making for simplicity and certainty in operation by unskilled labor of the large number of heaters required in an orchard.

The air-admitting opening 27 is placed in the generally horizontal central plate-like portion 26a of body 26, and is preferably semi-circular in shape as shown in Figs. 2 and 4. The flow of air through opening 27 into the upper end of draft tube 18 and thence into chamber 16 is regulated by draft-regulating plate 28 which is also generally semi-circular in outline and is shown as having a recess or notch 47 located preferably at or adjacent the middle of its semi-circular edge. Plate 28 is attached near its straight edge to resilient wire 35 which is pivotally mounted at its ends in body 26, as may be seen in Figs. 4 and 5. Wire 35 provides a hinge or pivotal mounting about which plate 28 swings, as may be seen from a comparison of Figs. 1 and 3.

The thermostatic control means comprises a coiled bimetallic element 30 which is attached in any suitable manner at one end to bracket 37. Bracket 37 is attached to plate 26a by any suitable means, as by rivets, and is preferably heat-

insulated from direct engagement with the plate by a layer of insulation 38, as seen best in Fig. 6, to retard the rate of heat transfer to the thermostat. Bimetallic strip 30 curves through almost one complete turn or circle when it is cold, and occupies a position shown in Fig. 5. In this position, it is engaged by a holding member in the form of curved arm 40 which is attached to the underside of plate 28 and projects downwardly therefrom in such a manner that the end of arm 40 bears against the side of bimetallic element 30. Engagement of arm 40, which constitutes a downwardly projecting portion of plate 28, with the bimetallic element holds plate 28 raised in the upwardly tilted position illustrated in Fig. 1.

In response to heat generated by the vaporizing flame within vaporizing chamber 16, bimetallic element 30 straightens out somewhat and reaches a position similar to that illustrated in Fig. 4 in which the arm 40 no longer engages the bimetallic element. When arm 40 disengages the bimetallic element, plate 28 drops suddenly under the influence of gravity to a lowered position such as shown in Figs. 3 and 4. In the extreme lowered position, the edge of plate 28 lies against the portion of body plate 26a which forms a margin around opening 27, because the dimensions of plate 28 are slightly larger than those of opening 27. However, under some circumstances it may be desired that plate 28 be not allowed to reach this extreme lowered position, but that its downward movement be limited to a position such as is shown in Fig. 3 in which the plate is not entirely closed. For this purpose, some type of limiting or stop means may be employed; and a preferred type of limiting means employed in my invention comprises a cam 42 which lies against the underside of plate 26a and bears thereagainst. Cam 42 is mounted upon a short shaft 43 which is preferably provided with a square shank passing through a round hole in body plate 26a, the shaft preferably having a head on its lower end. Not only does the square shank hold the cam against rotation with respect to the shank so that the cam can be rotated about the shank axis into adjusted positions by turning the shank, but the shape of the shank makes it possible to turn it by means of a detachable key or wrench of the proper size. The outline of cam 42 may be a spiral or eccentric curve or other outline of varying radius about the axis of cam rotation. Lever 45, having one end flattened, is secured to squared shank 43 and rests against the upper face of plate 26a. This cam assembly is completed by pin 46 which passes through shank 43 and bears against the flat end of lever 45 to hold shank 43 against dropping downwardly through plate 26a.

While it is not necessary that shank 43 be square, it is preferred that it be some shape other than round, in order that the cam and hand lever 45 may be non-rotatably affixed to the shank and that the latter may be turned by a detachable key. If a key or the like is not used, lever 45 may be used to rotate shank 43 in adjusting the position of cam 42; and if a key is used, lever 45 serves as visual means to indicate the position of cam 42.

Bimetallic element 30 and cam 42 are preferably enclosed within housing 31, not only to protect these parts against physical injury, but also to insulate the thermostat from the vaporizing flame and thus properly delay the response of the thermostat to heat received from the flame

in chamber 16. For this reason, the interior walls of housing 31 are lined with a layer of insulating material 49, such as asbestos or the like. It is preferable to extend the top layer of insulation 38 entirely across the interior of housing 31, as shown in Fig. 6. To facilitate this, plate 26a is preferably provided with a pair of elongated bosses 48 which space the layer of insulation 38 from the under side of plate 26a sufficiently that it clears cam 42 and passes just above bimetallic element 30.

The operation of my improved draft-regulating device will now be described briefly. Assuming the reservoir to have been filled with a body of liquid fuel 12 to the proper level, the heater is now ready to be lighted. To accomplish this, an attendant first raises the outer edge of draft-regulator plate 28 and swings the plate clockwise about its hinge until the plate passes top dead center and rests against the top of shaft 43, which acts as a stop to hold the plate in this open position, as shown by dotted lines in Fig. 1. The attendant then inserts the tip of his lighting torch in opening 27 and discharges a suitable quantity of a burning ignition fluid, which may comprise a mixture of gasoline and kerosene or the like, through opening 27 onto wick 19. A portion of this burning fluid falls down upon the surface of fuel body 12. The ignition fluid, burning on the surface of fuel body 12 and around wick 19, establishes a vaporizing flame which heats the liquid fuel sufficiently to effect generation of fuel vapor therefrom, and this vapor is carried into the stack 15 by the draft through the vaporizing chamber. When the rate of evolution of fuel vapors is adequate, the main combustion flame of the heater is established within or above the stack assembly 15, and it will be understood that some ignition fluid may be poured into the stack to facilitate ignition of the fuel vapors within the stack.

After the tip of the lighting torch is removed from opening 27, plate 28 is manually rotated counter-clockwise to the full line position of Fig. 1 in which arm 40 engages the side of bimetallic element 30 in the manner shown in Fig. 5. In this first or initial operating position, regulating plate 28 is raised above body plate 26a and allows maximum passage of air through opening 27. Draft-regulating plate 28 is gravity biased in the first position toward a closed position and is held in this first position, by engagement of arm 40 with bimetallic element 30, against gravity which tends to move the plate counter-clockwise into a second or closed position in which the passage of air through opening 27 is more or less restricted. All the time that the regulating plate is held in this first position, a relatively large amount of air is admitted to vaporizing chamber 16 and the vaporizing flame maintained therein burns at a relatively high rate. The heat from this vaporizing flame is transmitted to bimetallic element 30 by conduction and radiation from the metal parts of the draft tube and regulating device, and in response to this heat received thermostat 30 tends to straighten out.

The curvature of the thermostat is preferably such that all movement of the free end of the thermostat is substantially at right angles to the path of movement of plate 28 and arm 40 and consequently the straightening movement of the thermostat, while engaging arm 40, causes substantially no movement of arm 40 that raises or lowers draft plate 28. Eventually the quantity of heat received by bimetallic element 30 is such

that the free end of the thermostat element moves past and disengages the end of arm 40, reaching some such position as shown in Fig. 4. As the free end of bimetal strip 30 moves past the end of arm 40 out of engagement with the arm, plate 28 drops under the influence of gravity to its second operating position in which the flow of air through opening 27 is restricted to a greater or lesser extent according to the amount of closure permitted plate 28.

The position of draft plate 28 in its second or air-restricting position is determined in general by the position of cam 42. If cam 42 is turned in a counter-clockwise direction as viewed in Figs. 4 and 5 for approximately one-fourth revolution, then a portion of the involute cam of relatively small radius is turned opposite arm 40 and plate 28 is allowed to drop until it comes into contact with plate 26a, which limits further movement of the plate. Plate 28 is now at its point of maximum closure; but even then the opening 27 is not entirely closed because the recess or indentation 47 in the edge of plate 28 continues to permit a certain amount of air to pass through opening 27 and reach the vaporizing flame. The vaporizing flame is reduced in size and ability to vaporize fuel as a consequence of its reduced air supply, and under these conditions the main vaporizing flame in stack 15 is also reduced to a minimum.

When cam 42 is in the position of Fig. 4, the edge of arm 40 engages the edge of cam 42 when draft plate 28 has dropped to the position of Fig. 3, and before the point of maximum closure of the plate has been reached. In this position, less restriction is afforded on the amount of air passing through opening 27 than under the conditions previously described, because there is space between plates 28 and 26a through which air may pass to reach opening 27. This opening is in addition to the opening afforded by the recess 47 in the edge of plate 28. As a consequence of the somewhat increased air supply to the vaporizing flame, more fuel will be vaporized and the main combustion flame will burn higher.

A still higher fire in stack 15 may be secured by rotating cam 42 in a clockwise direction as viewed in Fig. 4, any desired amount up to approximately a quarter revolution. In its new position, the portion of cam 42 opposite arm 40 is of greater radius and engages the edge of arm 40 when plate 28 is in a higher position than in Fig. 3. Consequently, the gap between plates 28 and 26a is increased and a still greater amount of air is allowed to enter through opening 27, the increased amount of air causing the vaporizing flame to burn higher than under the conditions previously described.

From this discussion it will be seen that the second operating position into which the draft-regulating plate falls under the influence of gravity after arm 40 has become disengaged from bimetallic element 30, may be varied somewhat with respect to plate 26a by a limiting means, such as cam 42. In this second position of draft-regulating plate 28, the quantity of air flowing through opening 27 is restricted to a greater or lesser extent accordingly as plate 28 is nearer or farther from plate 26a, and the burning rate of the vaporizing flame is controlled by the quantity of air admitted. But in any event, the air admitted through opening 27 is less than that admitted when the draft plate is in its original position for admission of the maximum amount of air to the newly lighted flame and before the

draft plate has been released by thermostat 30 in response to heat received from the vaporizing flame.

The rate of heat transferred to thermostat 30 depends upon the quantity and efficiency of the insulating means 38 and 46 within housing 31; and the period of time required for the thermostat to release plate 28 may be increased or decreased respectively by increasing or decreasing the amount of insulation within the housing. The insulation preferably entirely surrounds the bimetal strip, or substantially so. For any particular type of heater, the correct amount of insulation may be determined by experiment, and should be made such that the maximum amount of air is admitted to the vaporizing flame for a sufficient time to insure an adequate heating of the fuel body and the generation of an adequate amount of fuel vapor within chamber 16. A T-shaped slot is cut in one side of housing 31 to permit cam 42 and arm 40 to operate through the housing wall.

After the fire in the heater has been put out by extinguishing the vaporizing flame, thermostat 30 cools and tends to return to its initial position as shown in Fig. 5. However, as will be seen from Fig. 4, the bimetallic element cannot do this since its free end now comes into contact with the side of arm 40. After this engagement, continued cooling of the bimetallic element does not change its position but merely causes it to press lightly against the side of arm 40; and because of the circular shape of the thermostat no damage is done to it since the pressure is not sufficient to cause any permanent deformation of the bimetallic element. The parts remain in this position until it is desired to again light the heater, at which time draft plate 28 is lifted as previously described; and the act of lifting the draft plate removes arm 40 from engagement with thermostat 30 which latter can then spring back to its normal position when cold, that is, the position shown in Fig. 5. When the draft-regulating plate is again lowered to its initial operating position, arm 40 comes into contact with the side of thermostat 30, and the draft-regulating device is reset to repeat the cycle of operations previously described. Recess 47 serves as a finger hole to grip the plate and lift it.

The coiled shape of thermostat 30 is of definite advantage in preventing injury to this element. In the event that regulating plate 28 should be forced downwardly when it is occupying the starting position shown in Fig. 1 with arm 40 engaging the bimetal strip, no damage is done to the parts because the bimetallic element has sufficient resilience to yield and allow the plate to be pushed down into contact with body plate 26a. Movement of this type simply causes the thermostat to be forced into a coil of smaller radius without causing any harmful or permanent deformation of the thermostat which would impair its operation. Additional safeguard against injury of the parts is provided by wire hinge 35. If draft plate 28, when in a lowered or air-restricting position and in engagement with cam 42, as shown in Fig. 3, is forced downwardly, hinge 35 simple bows slightly and permits the draft plate to rock about its point of engagement with the limiting cam until the plate comes in contact with body plate 26a. As soon as pressure on the plate is released, the hinge springs the plate back to its proper position. The plate is preferably attached to wire 35 near the mid-point of the latter to obtain the full

benefit of the resilient character of the hinge. Spring hinge 35 is preferably made of some material that will not lose its resilient characteristics after being repeatedly subjected to relatively high temperatures.

It is preferable, though not necessary, that draft plate 28 be so shaped as to never fully cut off the flow of air through opening 27 but be capable only of imposing restriction upon the air flow up to some predetermined maximum extent. In the form of the invention previously described, this was accomplished by providing notch 41 at the edge of plate 28 which left a portion of the opening 27 permanently uncovered. Variational forms of the draft-regulating plate which accomplish this same object, are shown in Figs. 7 to 10 inclusive, from which it will be seen that still other shapes of the draft plate may be employed within the scope of my invention.

In Figs. 7 and 8 there is shown a draft-regulating plate 28a of which the curved margin has been turned upwardly at right angles to the main portion of the plate to form an upturned flange 50. The flange is highest at its center opposite indentation 32 and tapers away in either direction from that point to the face of the plate. The upturned flange 50 not only provides a projection by which the draft plate may be lifted after it has dropped into lowered position, but it also leaves a crescent-shaped portion 51 of opening 27 which is not covered by the draft plate and so remains open to admit air even when the draft-regulating plate is in its position of maximum restriction of air flow.

Draft plate 28b in Figs. 9 and 10 illustrates another modification of the forms which may be given to the draft-regulating plate. In this form, a sector of the plate is turned upwardly along a line representing a chord parallel to hinge 35. Flange 53 formed in this manner provides a convenient projection for grasping the plate when it is desired to lift it from the closed position and manually reset the device for further operation. The turned-up portion of plate 28b forming flange 53 leaves a sector-shaped opening 54 when the draft plate is fully closed as shown in Figs. 9 and 10, and this sector-shaped opening 54, which is a portion of air-admitting opening 27, remains permanently uncovered by the draft plate to admit air even when the draft plate is in its position of maximum air restriction.

In all other features of construction and operation the modifications of my invention illustrated in Figs. 7 to 10 inclusive are the same as have been previously disclosed in connection with the description of Figs. 1 to 6.

Having described a preferred embodiment of my invention and certain modifications thereof, it will be understood that various changes in the shape, construction, and arrangement of the various parts may be made without departing from the spirit and scope of my invention; and consequently it is desired that the foregoing disclosure be considered as illustrative of, rather than limitative upon, the invention set forth in the appended claims.

I claim:

1. In association with a vaporizing type liquid fuel orchard heater provided with a vaporizing chamber having an air-admitting opening for maintaining a vaporizing flame within said heater at a place removed from the main flame, a heat-responsive draft-regulating device which comprises: a pivotally mounted regulating plate

disposed adjacent said opening and movable between a first position affording relatively free passage of air to the vaporizing chamber through said opening and a second position restricting the

5 passage of air through said opening, said plate being biased toward the second position and having a downwardly projecting arm; and thermostatic means disposed in heat-receiving relation to the vaporizing flame within the heater, 10 said thermostatic means comprising a bimetallic element engaging the projecting arm to hold the plate in the first position, and operable in response to heat generated by said vaporizing flame to release the plate and permit the plate to move into said second position; and a rotatably adjustable cam member engaged by the projecting arm as a result of said movement of the plate to limit the restriction imposed by the plate on passage of air through the opening.

2. A heat-responsive draft-regulating device 20 for an orchard heater, which comprises: a body member having an air opening; a draft-regulating plate pivotally mounted on the body adjacent said opening and movable between a first 25 position affording relatively free passage of air through the opening and a second position restricting passage of air through the opening, said plate being biased toward the second position; and thermostatic means engaging the plate, said thermostatic means comprising a coiled bimetallic element curved in a plane at right angle to the plane of movement of the plate that is adapted to hold the plate in the first position and is operable in response to heat generated within 30 the heater to release the plate and permit the plate to move into the second position, the movement of the bimetallic element at the point of said engagement in response to heat being substantially at right angles to the path of movement of the plate and effecting substantially no movement of the plate while engaging the latter.

3. A heat-responsive draft-regulating device 45 for an orchard heater, which comprises: a body member having an air opening; a draft-regulating plate pivotally mounted on the body adjacent said opening and movable between a first position affording relatively free passage of air through the opening and a second position restricting passage of air through the opening, said plate being biased toward the second position; thermostatic means engaging the plate, said thermostatic means comprising a coiled bimetallic element curved in a plane perpendicular to the plane of movement of the plate that is adapted to hold the plate in the first position and is operable in response to heat generated within the heater to release the plate and permit the plate to move into the second position; and heat insulating means substantially entirely surrounding the bimetallic element to retard the transfer of heat to and from the bimetallic element.

4. A heat-responsive draft-regulating device 55 for an orchard heater, which comprises: a body member having an air opening; a draft-regulating plate pivotally mounted on the body adjacent said opening and movable between a first position affording relatively free passage of air through the opening and a second position restricting passage of air through the opening, said plate being biased toward the second position and having a downwardly projecting arm; and thermostatic means engaging the plate, said thermostatic means comprising a coiled bimetallic element curved in a plane at right angles to

the plane of movement of the plate that is adapted to hold the plate in the first position and is operable in response to heat generated within the heater to release the plate and permit the plate to move into the second position; and a plate-like member adjustably mounted on and beneath the body in a position to engage the projecting arm as a result of downward movement of the plate to limit the restriction imposed by the plate on the passage of air through the opening.

5. A heat-responsive draft-regulating device for an orchard heater, which comprises: a body member having an air opening; a draft-regulating plate pivotally mounted on the body adjacent said opening and movable between a first position affording relatively free passage of air through the opening and a second position restricting passage of air through the opening, said plate being biased toward the second position; thermostatic means engaging the plate, said thermostatic means comprising a bimetallic element adapted to hold the plate in the first position and operable in response to heat generated within the heater to release the plate and permit the plate to move into the second position, the movement of the bimetallic element at the point of said engagement in response to heat being substantially at right angles to the path of movement of the plate and effecting substantially no movement of the plate while engaging the latter; and a rotatably mounted member adapted to determine the position of the plate and the restriction imposed by the plate on passage of air through the opening when the plate is moved to said second position.

6. A heat-responsive draft-regulating device for an orchard heater, which comprises: a body member having an air opening; a draft-regulating plate pivotally mounted on the body adjacent said opening and movable between a first position affording relatively free passage of air through the opening and a second position restricting passage of air through the opening, said plate being biased toward the second position; a holding member; and thermostatic means holding the plate in the first position by engagement with the holding member and operable in response to heat generated within the heater to move out of engagement with the holding member and release the plate to permit the plate to move freely into the second position, said thermostatic means comprising a coiled bimetallic element curved in a plane at right angles to the plane of movement of the plate, the movement of the bimetallic element at the point of said engagement in response to heat being substantially at right angles to the path of movement of the plate and causing

substantially no movement of the plate during engagement of the bimetallic element and said holding member.

7. A heat-responsive draft-regulating device for an orchard heater, which comprises: a body member having an air opening; a draft-regulating plate pivotally mounted on the body adjacent said opening and movable between a first position affording relatively free passage of air through the opening and a second position restricting passage of air through the opening, said plate being biased toward the second position; and fixed thermostatic means mounted on the body member to engage a portion of the movable plate and hold the plate in the first position, said thermostatic means comprising a coiled bimetallic element having a free end that engages said plate and is movable in response to heat generated by the heater to disengage the plate and permit the plate to fall freely into the second position, the bimetallic element being so positioned that movement of the free end of the element at the point of said engagement is substantially at right angles to the path of movement of the plate at that point and causes substantially no movement of the plate during engagement therewith.

8. A heat-responsive draft-regulating device for an orchard heater having a vaporizing flame within the heater, which comprises: a body member having an opening admitting air to maintain the vaporizing flame; a draft-regulating plate pivotally mounted on the body adjacent said opening and movable between a first position affording relatively free passage of air through the opening and a second position restricting passage of air through the opening, said plate being biased toward the second position; a holding member; and thermostatic means disposed in heat-receiving relation to the vaporizing flame and holding the plate in the first position by engagement with the holding member and heat operable to move in engagement with the holding member before reaching a position out of engagement with the holding member, said thermostatic means comprising a bimetallic element having a free end that engages said holding member and is movable in response to heat generated by the vaporizing flame to disengage the holding member and permit the plate to move freely into the second position, the bimetallic element being so positioned that movement of the free end of the element at the point of said engagement is in a direction that causes substantially no movement of the plate during said engagement.

JAMES R. CAMPBELL.
